CLAIM

The ornamental design for a combined high flow lifter and base, as shown and described.

DESCRIPTION

FIG. 1 is a top perspective view of a combined high flow lifter and base showing my new design.

FIG. 2 is a top perspective view of the lifter of FIG. 1.

FIG. 3 is a bottom perspective view of the lifter of FIG. 1.

FIG. 4 is a top perspective view of the base of FIG. 1.

FIG. 5 is a bottom perspective view of the base of FIG. 1.

FIG. 6 is a top plan view of the lifter of FIG. 1.

FIG. 7 is a bottom plan view of the lifter of FIG. 1.

FIG. 8 is a front elevation view of the lifter of FIG. 1.

FIG. 9 is a rear elevation view of the lifter of FIG. 1.

FIG. 10 is a left elevation view of the lifter of FIG. 1.

FIG. 11 is a right elevation view of the lifter of FIG. 1.

FIG. 12 is a top plan view of the base of FIG. 1.

FIG. 13 is a bottom plan view of the base of FIG. 1.

FIG. 14 is a front elevation view of the base of FIG. 1.

FIG. 15 is a rear elevation view of the base of FIG. 1.

FIG. 16 is a left elevation view of the base of FIG. 1; and,

FIG. 17 is a right elevation view of the base of FIG. 1.

The high flow lifter and base are shown separately in FIGS. 2 through 17 to show aspects of the design that are not visible when combined.

The broken lines in the drawings illustrate portions of the combined high flow lifter and base which form no part of the claimed design.

1 Claim, 17 Drawing Sheets
